Primary Examiner — Holly E Thurman

(74) Attorney, Agent, or Firm — Thomas | Horstemeyer,
LLP(57) **CLAIM**

The ornamental design for a rucksack, as shown and described.

DESCRIPTION

1.0 is a front view of a rucksack, showing my new design. The broken line showing portions of the rucksack are included for the purpose of illustrating the environmental structure and forms no part of the claimed design.

1 Claim, 1 Drawing Sheet
